TEXTILE HANDLING

Louis Spinelli, Paterson, N. J.

Application March 25, 1947, Serial No. 736,921

5 Claims. (Cl. 164—17)

1

My invention relates to textile handling and more particularly to a cloth laying machine and method for facilitating and laying cloth or the like in screen printing.

In screen printing of cloth or the like, a plurality of relatively long tables are disposed in spaced parallelism and provided on one side of each table with a lengthwise extending rail projecting above the surface of the table and equipped with a plurality of spaced stops or guides for engaging and positioning a printing frame, which is disposed over cloth laid on the table, for printing a design on the cloth. Heretofore, the cloth was laid over padding secured to the top surfaces of the tables and manually smoothed thereover to eliminate wrinkles and creases and then fastened to padding by a multiplicity of pins applied through the margins of the cloth. Upon printing of the cloth, the pins were removed and the cloth raised above the tables for drying of the printing in the usual manner. Obviously, this method of applying the cloth to the table necessitated considerable labor and expense especially with respect to the activity required in the elimination of wrinkles and creases and accuracy of alignment during laying.

My invention overcomes the foregoing difficulties and disadvantages, it being one of the objects thereof to provide means for expeditiously laying or applying the cloth to the table in a manner to preclude wrinkling and creasing.

Another object of my invention is to provide a cloth laying or applying machine which functions in conjunction with the printing rail of the table to effect accurate laying of the cloth.

A further object of my invention is to provide a machine of the foregoing described character which is so constructed and arranged whereby the machine may be easily shifted from one table to another for expediting the application of cloth to a plurality of tables.

A still further object of my invention is to provide, in conjunction with the cloth laying machine, means for shifting the machine from one table to another in an expeditious manner.

An important object of my invention is to provide means for shifting the machine which is so constructed and arranged as to insure proper positioning of the machine with respect to the table, thus permitting accurate laying of the cloth.

A special object of my invention is to provide a method whereby cloth may be expeditiously applied to the surface of a table in a minimum of time and with an appreciable reduction in labor and expense.

2

Another special object of my invention is to provide means of the foregoing described character which is simple in construction, durable in use, efficient in operation, economical in manufacture and which lends itself to high production methods.

With the above and other objects in view, as will hereinafter appear, the invention consists in the combination and arrangement of parts herein-
10 after set forth and illustrated in the accompanying drawings from which the several features of the invention and the advantages attained thereby will be readily understood by those skilled in the art.

15 Referring to the drawings wherein like reference characters designate like parts throughout the several views:

Figure 1 is a perspective view of my cloth laying machine and illustrating the same in operating position on a printing table.

20 Figure 2 is a perspective view of one end of a printing table having one of the dollies connected thereto and from which the cloth laying machine has been shifted onto the table.

25 Figure 3 is a fragmentary end elevation of the cloth laying machine illustrating the same in operating position on a portion of one of the tables, the latter being shown in section.

Figure 4 is a side elevation of the machine mounted on one of the dollies with the latter connected to an end of one of the tables.

30 Figure 5 is a longitudinal sectional view illustrating the machine in operating position on one of the tables.

35 Figure 6 is an end elevation, partly in section, of one of the guide roller assemblies.

Figure 7 is a sectional view taken on the line 7—7 of Figure 6.

Figure 8 is a diagrammatic top plan view of the table arrangement and steps in the shifting of the dollies.

Figure 9 is a view similar to Figure 5 but illustrating a modified form of the machine.

Figure 10 is a sectional view taken on the line 40 10—10 of Figure 9.

Figure 11 is an end elevation of a modified form of guide roller assembly.

In practicing my invention, as illustrated in the drawings, I employ a quaternary of relatively long printing tables, 10, 11, 12 and 13, respectively, of ordinary construction, disposed in parallel side by side spaced relation with each of the tables being provided on one side with a longitudinally extending printing frame guide or rail 14. The rail is L-shaped and is equipped with a plurality of spaced stops 15 on its vertical

flange for coaction with a printing frame to effect proper positioning of the latter over the cloth to be printed. The top of the table is provided with a padding which includes an outer layer of suitable fabric 16 or the like on which a length of the cloth 17 to be printed is laid thereover and secured thereon against displacement by any suitable means, for instance, by pins applied through the cloth and the outer layer 16 of the padding in the usual manner.

In order to expedite the laying of the cloth 17, I provide a cloth applying or laying machine 18 for detachable mounting upon a pair of dollies 19 and 20 for disposition in proximity to opposite coincident ends of the tables respectively. Each dolly comprises a quaternary of legs having their lower ends equipped with swivelled rollers or casters and their upper ends secured to a platform 21. One side of the platform 21 is provided with a rail 22 similar to the rail 14 of the table and with the ends of the rail 22 having pivoted thereto a bridge member or latch 23 for engagement with the end of the rail 14 of a table for attaching the dolly thereto whereby the machine 18 may be shifted from either the dolly or table, as the case may be, for operations hereinafter more fully described.

The machine comprises a frame having end and side members 24 and 25 respectively, and a pair of relatively large cloth applying rollers 26 disposed within the confines of the frame and which are provided with trunnions journaled in bearings 27 depending from the side frame members 25 whereby the frame is supported by the rollers. The side frame members 25 have connected thereto upwardly extending standards 28 equipped on their upper ends with open bearings 29 formed with inverted V-shaped slots having rollers extending therein on which are received the ends of a mounting shaft 30 on which is mounted a roll of the cloth 17 to be printed. A pair of spaced arms 31 extend outwardly from the standards 28 and each has journaled in its outer end a trunnion 32 of a bearing plate 33 in which is rotatably journaled coincident ends of a pair of spaced tension rods or rollers 34 between which is trained the free or leading end section 35 of the cloth, the latter extending under the rollers 26. The outer ends of the arms are each bifurcated and provided with a clamping screw and wing nut to clamp the respective trunnion 32 to its arm whereby the plates 33 and rollers 34 are secured in adjusted position, relative to the arms, to maintain a desired tension on the cloth.

The inner ends of the arms 31 are pivoted to the standards, subjacent the bearings 29, and are engaged by blocks 36 slidably mounted thereunder on the standards and which engage the inner end sections of the arms to maintain the arms in raised position above the frame. Subjacent the blocks 36, the standards are provided with plates 37 fixed thereto and spaced from the blocks and which plates have threaded therein adjusting screws 38 engaging the blocks 36 and operable for raising and lowering the arms whereby the outer ends of the arms 31 may be adjusted relative to each other for insuring proper guiding of the free end of the cloth, from the roll, to the initially receiving roller 26 and thus parallel the side margin of the cloth with the rail 14 for a purpose hereinafter more fully understood.

To effect accurate guiding of the machine over the table, the under face of one side of the

frame, at each end thereof, has secured thereto a guide roller assembly comprising a pair of depending integral inner and outer bearing sleeves 39 and 40 in which are slidably mounted the upper ends of inner and outer shafts 41 and 42 respectively, springs 43 being incorporated within the bore of each of the sleeves 39 and interposed between the under face of the frame and the top of the respective shaft 41 for urging the latter downwardly. Each pair of the inner and outer shafts 41 and 42 are connected together as at 44 to effect unitary reciprocation thereof in the sleeves 39 and 40. The lower ends of the shafts 41 and 42 have mounted thereon inner and outer rollers 45 and 46 for engaging the side faces of the vertical flanges of the rails 14 and 22 respectively, whereby the machine is guided over the table or on or off of one of the dollies. The lower end of each of the inner shafts 41 is bifurcated and has mounted therein a roller 47 for tracking engagement with the horizontal flanges of the rails 14 and 22 on the table and dollies to maintain the rollers 45 and 46, when on the rail 14, out of engagement with the horizontal flange and below the stops 15 on the vertical flange at all times and thus preclude engagement of the rollers 45 and 46 with the stops 15 in the event that the padding, on the particular table, be of a thickness or compressibility to effect vertical movement of the frame relative to the rail 14, by the rollers 26.

Each of the inner bearing sleeves 39 is provided with an axially extending slot 48 through which extends a guide pin 49 carried by the respective inner shaft 41 whereby to maintain the upper end of the shaft in the sleeve, limit vertical movement of the latter and to preclude rotation relative to the sleeve, it being understood that inasmuch as the adjacent outer shaft 42 is connected to the inner shaft 41, as at 44, the movement of said outer shaft will be likewise limited.

Inasmuch as the platform of either or both of the dollies may, in some instances, be either higher or lower than the table, the relative height of the horizontal flanges of their rails will likewise vary thereby establishing an abutment at the jointure of a dolly and a table and which would engage the rollers 45 and 46 upon shifting of the machine from the lower to higher horizontal flanges. In order to overcome this difficulty, the lower end sections of the inner shafts 41 are each provided with oppositely extending guide plates 50 for paralleling the vertical flanges of the rails and with each formed at its outer end with an inwardly and downwardly inclined cam face 51 for engaging the higher horizontal flange during shifting of the machine and thereby effect raising of the particular corner of the machine a sufficient distance to permit the adjacent roller 47 to be shifted over the abutment and engage the higher horizontal flange for tracking therewith.

In order to preclude accidental shifting of the machine from off of either of the dollies, latch mechanism is provided wherein each dolly has secured to a side face thereof a keeper 52 provided at its upper end with a laterally disposed flange formed with a slot which receives the lower end of a latch bar 53, the upper end of the latch bar being pivotally connected to a bracket 54 secured to the side of the machine. The frame of the machine, adjacent the latch bar, has connected thereto one end of a spring 55, the opposite end of which is connected to the latch bar whereby the spring functions to urge the latch bar towards the machine and thus maintains the latch bar

in the slot of the keeper. Obviously, by moving the outer end of the latch bar outwardly, against the tension of the spring, it is released from the keeper and permits shifting of the machine onto the table.

In operation—assuming the machine is positioned on the dolly 19 with a roll of cloth mounted thereon and having its free end trained under the rollers 26 and with the dolly 19 being secured to the end of the table 10 by the latch 23 connecting the rails together—the machine is shifted from the dolly 19 onto the table 10 and operated over the surface thereof. As the machine is thus operated, the cloth is unwound from the roll and accurately and smoothly laid over the surface. Either previous or subsequent to the foregoing operation, the dolly 20 has been connected to the opposite end of the table 10 and thus receives the machine thereon whereupon the cloth is transversely severed to permit the cloth on the table to be secured to the latter as desired. When the machine has thus been shifted onto the dolly 20 the latter is disconnected from the table 10 and operated over the floor in a manner to permit the rail of the dolly 20 to be connected to the rail of the adjacent table 11 by the latch 23, for instance, by rotating the dolly 180° as indicated by dotted lines 56 in Figure 8. When the dolly 20 is thus connected to the table 11 and the dolly 19 is disconnected and moved from the table 10 into connected relation with the table 11, as indicated by the dotted lines 57, the machine is then operated over the table 11 and onto the dolly 19, whereupon the latter is moved into connected relation with the table 12 over the path indicated by the dotted lines 58 while the empty dolly 19 is shifted from the table 11 to the table 12 over the path 59. The machine is then operated over tables 12 and 13 in the same manner as set forth in connection with tables 10 and 11, the dollies being shifted accordingly. When the machine has been operated over table 13 and onto dolly 19, the latter and the empty dolly 20 are then disconnected from the ends of the table 13 and shifted into connected relation with coincident ends of the table 10 over the paths 60 and 61 whereby another cycle of the foregoing operations is had to again lay cloth on the tables 11 to 13 inclusive, it being understood that the lengths of cloth operated upon or treated are removed from the tables to permit other lengths of cloth to be laid over the surfaces of the tables. At the start of each cloth laying operation, the free end of the cloth is secured to the particular table upon shifting of the machine from the dolly onto the table and, upon termination of each cloth laying operation and shifting of the machine onto a dolly, the cloth is transversely severed to permit the end severed from the roll to be secured to the table and shifting of the dolly and machine away from the table.

In instances where the space at the ends of the tables is of a limited nature to preclude rotation of the dollies 180°, each dolly may be laterally shifted to the coincident end of the adjacent table and the arms 31 rotated about their pivots to position the tensioning rollers 34 on the opposite side of the roll of cloth as illustrated in dotted lines in Figure 4, the free end of the cloth being trained between the rollers 34 and under the rollers 26 in the opposite direction to permit the machine to be reversely operated. Inasmuch as the rails 14 of the tables are not always arranged on coincident sides, the opposite side of the machine, in these

instances, is also provided with guide roller assemblies 65 as indicated in dotted lines in Figure 10. Furthermore, as illustrated in Figures 9 and 10, the frame may be equipped with supporting brackets 70 on which is mounted an open top box 71 which accommodates a bolt of cloth 72 having horizontally disposed connected sections, in lieu of the roll 17, thus permitting cloth from a bolt to be withdrawn from the box and laid on the table as will be apparent from Figure 9.

As illustrated in Figure 11, when the tables and dollies are of a uniform height, the guide rollers 80 may be provided with non-adjustable vertical shafts 81 and connected together in pairs by means of a tie-rod 82 which in turn is connected to the frame of the machine.

Without further elaboration, the foregoing will so fully explain the invention that others may, by applying current knowledge, readily adapt the same for use under various conditions of service. Moreover, it is not indispensable that all the features of the invention be used conjointly since they may be employed advantageously in various combinations and subcombinations.

It is obvious that the invention is not confined to the herein described use therefore as it may be utilized for any purpose to which it is adaptable. It is therefore to be understood that the invention is not limited to the specific construction as illustrated and described, as the same is only illustrative of the principles involved which are capable of extended application in various forms, and the invention comprehends all construction within the scope of the appended claims.

What I claim is:

1. The method of laying cloth on a plurality of parallel spaced printing tables by means of a cloth laying machine comprising, the steps of arranging a carrier on which the machine is mounted at one end of one of said tables, shifting the machine from the carrier onto the table and operating the same over the table to lay a length of cloth thereover, shifting the machine from said table onto another carrier at the opposite end of the table, positioning said last mentioned carrier adjacent the coincident end of an adjacent table, shifting the machine from the last mentioned carrier onto said table and operating the same thereover to lay the cloth thereon, positioning said first-mentioned carrier adjacent the coincident end of said second mentioned table and of shifting said machine thereon, for operation thereover, and transversely severing said cloth upon shifting of the machine onto a carrier.

2. The method of laying cloth on a plurality of parallel spaced printing tables by means of a cloth laying machine comprising, arranging a pair of carriers at opposite ends respectively of one of said tables, progressively shifting the carriers to positions adjacent coincident ends of adjacent tables, and meanwhile, shifting the machine from one carrier onto another and over a table therebetween to lay cloth thereon, and transversely severing the cloth upon shifting of the machine onto a carrier.

3. In an apparatus for laying cloth on a table equipped with a guide rail, a frame, supporting rollers rotatably mounted on said frame for supporting the latter and feeding cloth onto the table, guide means carried by said frame for coaction with the rail to guide said rollers

over the table and thus lay the cloth over a predetermined path on said table, said means including vertically adjustable rail-engaging rollers and roller adjusting means coacting with said last mentioned rollers and the rail for effecting the adjustment of said rail-engaging rollers and maintaining said last mentioned rollers at a height with respect to the vertical flange of the rail to preclude engagement with stop members carried by said flange, supporting means carried by said frame for supporting a cloth supply for feeding a web to said supply rollers, cloth tensioning means pivotally connected to said frame and operable to positions on either side of the supply to permit operation of said apparatus in either direction over said table.

4. In an apparatus for laying cloth on a table equipped with a guide rail normally provided with printing device positioning means, a frame, rollers rotatably mounted on said frame for supporting the latter and feeding the cloth onto the table, adjustable guide means carried by said frame and coacting with the rail to effect adjustment of said guide means relative to said rail to preclude engagement with said positioning means and thus guide said rollers over said table, to lay the cloth over a predetermined path on the table, and means carried by said frame guide means for engaging said rail to permit easy shifting of said rollers onto said table from a carrier.

5. The method of laying cloth on at least a pair of spaced printing tables by means of a cloth laying machine comprising, arranging a pair of carriers at opposite ends respectively of one of said tables, shifting the carriers to positions adjacent the ends respectively of the other table, and meanwhile, shifting the machine from one carrier onto another and over the table therebetween to lay cloth thereon, and transversely severing the cloth upon shifting of the machine onto a carrier.
